UNITED STATES PATENT OFFICE.

MIKE VELK, OF BOSWELL, PENNSYLVANIA.

BOMB-THROWING MACHINE.

1,268,187.

Specification of Letters Patent.

Patented June 4, 1918.

Application filed April 5, 1918. Serial No. 226,867.

To all whom it may concern:

Be it known that I, MIKE VELK, a subject of the King of Hungary, residing at Boswell, in the county of Somerset and State of Pennsylvania, have invented certain new and useful Improvements in Bomb-Throwing Machines, of which the following is a specification.

The primary object of the invention is the provision of a bomb thrower adapted for operation without the employment of explosives whereby missiles may be hurled great distances with only slight expense.

A further object of the invention is the provision of a device for throwing missiles that is easy and inexpensive to manufacture arranged for adjustment whereby the distance to which the missiles are thrown may be regulated, the throwing operation being readily set by soldiers in charge of the device and tripped at any distant point desired.

In the drawing forming a part of this application and in which like numerals refer to corresponding parts throughout the several views:—

Figure 1 is a central longitudinal vertical sectional view of the device;

Fig. 2 is a side elevation thereof with a side portion thereof broken away and the mechanism arranged in its tripped position;

Fig. 3 is a top plan view of the device arranged as shown in Fig. 1; and

Fig. 4 is a vertical transverse sectional view taken upon line 4—4 of Fig. 1.

Referring more in detail to the drawing, the device comprises opposite sides 10 connected together by spaced rollers 11 and 12 journaled through the said sides while oppositely inclined toes 13 are carried by the sides 10 adapted to project into the ground 14 for anchoring the device in position when desired for use.

An arm 15 is secured to and radially projects centrally from the roller 12 having a receiving socket 16 in the enlarged head 17 thereof adjacent the free end of the said arm while curved prongs 18 are carried by the head adjacent the said socket for convenience in positioning a missile or cannon ball 19 within the socket.

An operating spring 20 is connected centrally to the roller 11 at the point 21 and is adjustably attached to the arm 15 by means of an I-bolt 22. It will be readily seen that

by positioning the ball 19 within the socket 16 and rearwardly depressing the arm head 17 as shown in Fig. 1 of the drawing, the spring 20 will be placed under tension and upon releasing the arm 15, the arm will swing forwardly for hurling the ball 19 in the desired direction. The tension of the spring 20 may be slightly adjusted by moving the bolt 22 longitudinally of the arm 15 whereby the length of the spring 20 will be regulated when the device is set so that the throwing distance may be slightly altered in this manner.

A cross bar 23 is arranged between the sides 10 adjacent the rear end of the device with a spring 24 centrally mounted thereon upon which the arm 15 is adapted to seat when in its set arrangement while a hook 25 serving as a trigger is pivoted at 26 to the bar 23 with its retaining end 27 engaging a keeper 28 upon the bottom of the said arm. By this means it will be seen that the arm 15 is swung rearwardly and depressed upon the spring 24 which will retain the trigger 25 in engagement with the keeper 28 when the device is set and until released by pivotally moving the trigger 25 in any desired manner such as by pulling upon the firing cord 29 attached to the lower end of the said trigger. The spring 24 also acts to assist the initial upward and forward swinging movement of the arm 15 during the operation of the device assisting the spring 20 at such times when the spring 20 is arranged in a plane approaching that of the plane of the arm 15.

The soldiers in charge of the device can manually depress the arm 15 and set the same with the trigger 25 in its engaging position and a ball 19 or other missile may be then positioned within the socket 16. The cord 29 may be grasped and pulled for releasing the trigger 25, permitting the spring 20 to operate the arm 15 and hurl the ball 19 as found desirable. The position of the device as a whole will be maintained normal by the engaging toes 13 of the side members 10. The device possesses great simplicity and is subject to little wear during operation while the length of its throw may be regulated by adjusting the bolt 22. It will also be evident that other forms of missiles than the ball 19 may be hurled by means of the device such for instance as explosive bombs or hand grenades.

What I claim as new is:—

1. A throwing device comprising a mounting means, parallel rollers carried thereby, a missile-supporting arm carried by one of the 5 rollers, an operating spring secured to the other roller and adjustably connected to the said arm whereby the tension of the spring is adapted for regulation when the arm is in its set arrangement prior to the operation of 10 the device.
2. A throwing device comprising a mounting means, parallel rollers carried thereby, a missile-supporting arm carried by one of the rollers, an operating spring secured to the 15 other roller and adjustably connected to the said arm whereby the tension of the spring is adapted for regulation when the arm is in its set arrangement prior to the operation of the device, seating means for a missile 20 arranged upon one side of said arm, a keeper upon the other side of the arm, a swinging trigger carried by the supporting means engaging the said keeper when the device is set, and resilient shifting means for the arm 25 adapted for contacting the arm at a point adjacent the said keeper.
3. A missile thrower comprising opposite parallel sides, anchoring toes inclined in opposite directions from the lower edges of 30 said sides, transverse rollers journaled in spaced relations in the said sides, a missile hurling arm radially projecting centrally of the rearmost roller having an enlarged head portion at its free end with a socket in its 35 forward face, missile-seating prongs carried

by said head adjacent the socket, an I-bolt carried by the arm adjustably arranged longitudinally of the arm, an operating spring connected between the other roller and the said I-bolt, and retaining means for the arm 40 when in its rearwardly lowered set arrangement.

4. A missile thrower comprising opposite parallel sides, anchoring toes inclined in opposite directions from the lower edges of 45 said sides, transverse rollers journaled in spaced relations in the said sides, a missile hurling arm radially projecting centrally of the rearmost roller having an enlarged head portion at its free end with a socket 50 in its forward face, missile-seating prongs carried by said head adjacent the socket, an I-bolt carried by the arm adjustably arranged longitudinally of the arm, an operating spring connected between the other 55 roller and the said I-bolt, a transverse bar arranged between the sides adjacent the rear end of the device, a vertically positioned coil spring arranged upon the bar upon which the said arm is adapted to seat when the 60 device is set, a keeper upon said head substantially opposite the socket thereof, a hook-shaped trigger pivoted to the bar adapted for engaging said keeper when the arm is in its depressed rear position, and a releasing 65 cord for the trigger attached to the lower end thereof and extending a distance rearwardly of the device.

In testimony whereof I affix my signature.
MIKE VELK.
